UNITED STATES PATENT OFFICE.

FREDERICK C. HARRIS, OF DULUTH, MINNESOTA.

SAFETY DEVICE FOR ELECTRIC SWITCHES.

1,159,668.

Specification of Letters Patent.

Patented Nov. 9, 1915.

Application filed June 11, 1914. Serial No. 844,422.

To all whom it may concern:

Be it known that I, FREDERICK C. HARRIS, a citizen of the United States, residing at Duluth, in the county of St. Louis and State of Minnesota, have invented certain new and useful Improvements in Safety Devices for Electric Switches; and I do hereby declare the following to be a full, clear, and exact description of the invention, such as will enable others skilled in the art to which it appertains to make and use the same.

This invention relates to a safety device and is more particularly adapted for use in connection with electric switches of the type known as the knife switch.

One of the objects of this invention resides in the provision of a safety device for electric switches composed wholly of non-conducting material, and which may be readily applied to any switch of well known construction.

A further object of this invention resides in the provision of a safety attachment or protector for electric switches provided with means for readily attaching the same to the same support which supports the electric switch.

A still further object of this invention resides in the provision of a safety protector for electric switches formed of nonconducting material and provided with means for preventing the accidental displacement of the handle of the switch. And a still further object of this invention resides in the provision of a safety attachment or protector for electric switches for wholly encompassing the metallic portions of the switch mechanism thus obviating all danger of personal contact of the body of the operator with the switch.

Another object of this invention resides in the provision of a safety device for electric switches which is simple in construction, efficient and durable in purpose and can be manufactured and sold upon the market at a nominal cost.

These and other objects will more fully appear and the nature of the invention more clearly understood by the construction, combination and arrangement of the parts thereof as described in the following specification, defined in the appended claim and illustrated in the accompanying drawings, in which,

Figure 1 is a perspective view of the safety device showing the manner of apply-

ing the same to an electric switch. Fig. 2 is a vertical longitudinal sectional view showing the switch within the safety device, the switch being shown with the circuit closed.

I desire to here state that the purpose of this invention is to meet a long felt want and to avoid the serious and oftentimes fatal accidents due to exposed electric switches, the invention consists of a safety protector or casing formed of any well known nonconducting material, though I preferably form the device of fibrous material, the same being capable of ready application to an electric switch without any alterations in the switch construction, and which may be made of any size in accordance with the size of the switch to which the protector is to be used.

Referring to the drawings, 1 denotes the switch support which may be the wall of a building, table, stand or other support, 2 denotes the base of the electric switch secured in any well known manner to the support 1, 3 the binding posts for receiving the incoming wires 4, 5 the pivot post of the binding post 3 in which is pivoted the knife switch 6 provided with the handle 7.

8 denotes corresponding binding posts for receiving the outgoing wires 9, the binding posts 8 being provided with the spring contacts 10 for receiving the knife switch 6.

The safety device or protector consists of an open ended box or casing comprising the bottom 11 provided with the slots 12 through which the incoming wires 4 pass to the binding posts 3 of the switch, the sides 13 formed of approximately quadrantic shape, and the curved quadra-circular top 14 provided at the upper end with the slots 15 for the passage of the outgoing wires 9 leading from the binding post 8 of the switch, the side edges of the bottom 11 and the top 14 are provided with a plurality of spaced dove-tailed recess 17 for receiving the dove-tailed 100 tongues 18 formed upon the edges of the quadrantic sides 13. When the parts of the protector are in assembled relation, the same forms a complete casing, excepting one end being open as shown at 19, this open end being provided for readily passing the protector or casing over the switch, the surrounding edges of the opening 19 engaging the support 1 of the switch and in this manner the metallic portions of the switch are entirely inclosed.

Formed in the circular top 14 is the elong-

gated slot 20 beginning at a point slightly removed from the open end 19 and extending downwardly and terminating at a point remote from the bottom edge of the casing, the 5 slot being of a width slightly greater than the diameter of the reduced portion of the handle 7 of the switch, the upper end of the slot 20 being circular and enlarged to provide for the passage of the enlarged portion 10 of the handle 7, which handle 7 projects outwardly through the slot 20 and is adapted to travel therein during the operation of the handle for the manipulation of the switch, the lower end of the slot 20 being rounded as 15 at 22 at which point the handle rests when the switch is thrown to open the circuit.

For preventing the accidental displacement of the switch handle 7 when the switch is thrown to open the circuit the inwardly 20 projecting curved lug 23 is provided in one of the side walls of the slot 20 and at a point adjacent the rounded end 22 of the slot 20, this lug 23 being so positioned as to prevent the handle 7 from being forced upwardly 25 by any accidental means, but does not prevent the handle from being thrown upwardly for closing the circuit when desired, and to provide for the passage of the reduced portion of the handle 7 by the lug 23, 30 the correspondingly curved recess 24 is formed in the opposite wall of the slot 20, thus it will be readily seen that when the handle 7 is resting in the rounded end 22 of the slot 20 that any accidental blow upon 35 the handle 7 will not force the handle 7 upwardly from the fact that the reduced portion of the handle comes in contact with the lug 23 and is thereby limited from further movement, however, should it be desired to 40 force the handle upwardly for closing the circuit it is only necessary to bend the handle laterally into the recess 24 whereby the handle will readily pass by the lug 23 and continue upwardly through the slot 20 until 45 the knife 6 properly engages the contact spring 10 of the switch thus closing the circuit.

The safety device or protector casing is applied to an electric switch in the following manner: The switch handle 7 is passed 50 through the enlarged circular opening 21 formed at the end of the slot 20 and the open end 19 passes over the switch, the incoming wires 4 pass in the slot 12 of the bottom 11, 55 the outgoing wires 9 passing through the slots 15 of the top 14, whereupon the edges

of the protector casing at the opening 19 will engage the surface of the electric switch support 1, the casing being secured to the support 1 by the L-shaped clips 25 having one of their arms riveted to the sides 13 as at 26, the remaining angular disposed arms of the clips 25 being secured to the switch support 1 by the screws or other suitable fastening means 27 and it is, therefore, obvious that 60 the switch is entirely inclosed excepting a portion of the handle 7 which projects outwardly through the slot 20 of the top 14 for manipulating the switch within the protector casing, and by such construction and application of the safety protector, it is impossible for any part of the person of the operator of the switch coming in contact with any of the metallic portions of the switch there being no dangerous exposed portions 70 of the switch mechanism.

While I have here shown and described the preferred form of my invention, I hereby reserve the right to make such alterations and variations therein from time to time as 80 I may deem expedient and which will neither depart from the spirit of this invention nor conflict with the scope of the claim.

Having thus fully described my invention what I claim as new and desire to secure by 85 Letters Patent of the United States is:—

A safety device, in combination with an electric switch, the handle thereof, and the support for said switch, of an open ended casing formed of nonconducting material 90 for inclosing the metallic parts of an electric switch, comprising a bottom, sides, and a top, said top formed with an elongated slot within which said handle operates, and an enlarged opening at the upper end of said 95 slot through which said handle is initially passed when applying said casing, said top also formed with a recess in one of the walls inclosing said slot and adjacent the lower end of said slot, and a lug upon the other 100 wall of said slot opposite said recess and projecting into said slot within the path of said handle to prevent the accidental displacement of said handle when positioned in the lower end of said slot.

In testimony whereof I have signed my name to this specification in the presence of two subscribing witnesses.

FREDERICK C. HARRIS.
